UNITED STATES PATENT OFFICE.

LAWRENCE G. REPELL, OF KANSAS CITY, MISSOURI.

KEY LOCK.

Application filed March 14, 1927. Serial No. 175,109.

My invention relates to improvements in key locks.

One of the objects of my invention is to provide a novel key lock adapted to be attached to a door and to releasably engage a key, which is in the lock of the door, to hold the key from being turned to the unlocked position by anyone at the outer side of the door.

10 A further object of my invention is to provide a novel key lock of the kind described, which is simple, cheap, portable, durable, not liable to get out of order, and which will efficiently perform the function for which it is designed.

The novel features of my invention are hereinafter fully described and claimed.

In the accompanying drawing which illustrates the preferred embodiment of my invention,

Fig. 1 is an inside elevation of a portion of a door to which is attached one of my improved key locks, a portion of the shank of the key being broken away, the parts being 25 in the locking positions.

Fig. 2 is an edge elevation of the same.

Fig. 3 is a view, enlarged, partly in elevation and partly in vertical section of my improved key lock, the front plate of the support being removed, and the securing member shown in section.

Fig. 4 is a section on the plane of the line 4—4 of Fig. 3.

Fig. 5 is a cross section on the plane of the line 5—5 of Fig. 3.

Fig. 6 is an enlarged perspective view of the rotary key engaging member.

Fig. 7 is a front view of the cover plate.

Similar characters of reference designate 40 similar parts in the different views.

1 designates a door having in its lock an ordinary flat shank key 2. For holding the key 2 from being turned from the locked position by a person at the outer side of the door, my improved key lock provides a support comprising a member 3 having a depending shank and provided at its upper end with a ringlike portion 4 having a transverse slot 5 in its lower portion, and a front 45 plate 6 fastened to said ringlike portion 4 by pins 7, preferably integral with the portion 4 and having a hole 8 therethrough which registers with a similar hole 9 in the portion 4, the shank of the key 2 being adapted to be extended through the holes 8 and 9 and through a peripheral notch 10 in

a circular rotary member 11 mounted in a circular recess 12 in the portion 4, and at the rear of the plate 6. The latter has a slot 5' registering with the slot 5. 60

The rotary member 11 has a peripheral and circumferential groove 13 one end of which terminates at the notch 10, and the other end of which terminates at a wall 14, 65 Figs. 3, 4 and 5.

In the portion 4 above the recess 12 is a recess 15, which is covered by the plate 6, and which is connected by a groove 16 with the recess 12. In the groove 16 is reciprocatively mounted a locking member 17, Fig. 70 3, which is pivoted by a pin 18 to an operating lever 19, which is pivotally mounted on a pin 20 in the recess 15, the end of the lever 19 which is distant from the locking member 17, being extended through a groove 21, 75 which extends from the recess 15 to the outer side of the portion 4. In the recess 15 is a spring 22 which bears against the lever 19, so as to cause the latter to normally force the locking member 17 into the recess 12, and 80 into the notch 10 when the rotary member is disposed as shown in Fig. 3, and the groove 16 registers with the notch 10.

In the position shown in Fig. 3, with the locking member 17 entering the notch 10, the 85 key 2 is in the locked position in the door 1, and the locking member 17 holds the rotary member 11 from being turned counterclockwise, so that the key 2 is held from being turned to the unlocked position by anyone 90 at the outer side of the door 1.

For attaching the device to the door 1, there is provided any suitable means, such as a screw hook having a threaded shank 23, Fig. 2, the outer end of the shank having a hook 24, and the shank having a longitudinal slot 25 which extends into the hook portion 24, Fig. 4. The shank 3 is slidably mounted in the slot 25, and is provided at its lower end with a spherical portion 26, of too 95 large a diameter to permit it to pass through the slot 25. When the device is freed from the key 2, the member 3 may be swung to a depending position on the screw hook, as 100 shown in dotted lines in Fig. 2. 105

The rotary member 11 is revolvable by the key 2 to a position diametrically opposite that shown in Fig. 3, and in such position, the notch 10 registers with the slot 5, and the shank of the key 2 can pass out of the notch 10 through the slot 5. To effect this, the shank 3 is slid upwardly in the slot 25 to the 110

position shown in dotted lines in Fig. 3, and the notch 10 being in register with the slot 5, the shank of the key will pass out through the slot 5. By reversing this movement, the 5 key shank may be inserted into the notch 10 through the slot 5. If the key 2 is then turned to the locked position shown in Fig. 3, the rotary member 11 will be turned to the position shown in Fig. 3, at which time, the 10 spring 22 will swing the lever 19 to force the locking member 17 into the notch 10, thereby holding the key 2 in the locked position.

To unlock the door, the lever 19 is pushed 15 downwardly at its upper outer end, against the pressure of the spring 22, so as to move the locking member 17 out of the notch 10, upon which the key and rotary member 11 may be turned counterclockwise, until the 20 locking member, traveling in the circumferential groove 13, strikes the wall 14, thus stopping the movement of the rotary member, with the notch 10 registering with the slot 5.

It will be noted that in the inner wall of 25 the groove 13 the member 11 is provided with teeth 27, Figs. 3 and 6, which are adapted to be engaged by the locking member 17, and which are adjacent to the notch 10. These teeth are provided to permit the locking 30 member 17 holding the key 2 from turning from a partly locked position, in cases where, due to sagging of the door, or for some other reason, the bolt of the lock can not be forced to the normal fully locked position, and the rotary member 11 can not be turned by the key to a position in which the 35 notch 10 will receive the locking member 17.

I do not limit my invention to the structure shown and described, as many modifications of my invention, within the scope of the 40 appended claims, may be made without departing from the spirit of my invention.

What I claim is:—

1. In a key lock, a support having a ring-like portion provided with a transverse slot

for the passage of a key shank, a member rotatable in said portion having a peripheral notch for receiving said shank, said member being revoluble to and from a position in which said notch will register with said slot, 50 a locking member movable on said support into and out of said notch when the rotary member is turned by the key shank to the locking position of the key and the notch is out of register with said slot, the key being 55 in an unlocked position when the slot and notch are in register, a lever on said support engaging and arranged to move said locking member to and from the locking position, and a spring for normally forcing said lever 60 to move said locking member to the locking position.

2. In a key lock, a support having a ring-like portion, provided with a transverse slot for the passage of a key shank, a member rotatable in said portion having a peripheral notch for receiving said shank, and having a peripheral groove terminating at one end at said notch and having at its other end a wall, said member being rotatable to and from a position in which said notch will register with said slot, a locking member movable on said support into and out of said notch when said rotary member is turned by 70 said shank to the locking position of the key and the notch is out of register with said slot, the key being in an unlocked position when the slot and notch are in register, said locking member being adapted to enter said groove and to contact with said wall to limit 75 the retracting movement of the rotary member when the latter is turned to the position in which the slot and notch register, and a lever engaging said locking member for moving the latter to and from the locking position.

In testimony whereof I have signed my name to this specification.

LAWRENCE G. REPPELL.
